Shoe Machinery Corporation, Flemington, N.J.,
a corporation of New Jersey

Application January 3, 1948, Serial No. 436

17 Claims. (Cl. 12—36)

1

This invention relates to shoe presses for pressing soles against shoe bottoms and is illustrated herein by way of example as embodied in a shoe repair press for cement attaching half soles to the foreparts of shoe bottoms.

Objects of the invention are to provide an improved shoe press of the type referred to which will be adapted to apply and sustain relatively heavy pressure against the shoe, will be simple in construction, economical to operate and yet will be capable of operating as fast and efficiently as the more complicated and expensive shoe presses in use today.

To the attainment of these ends, the invention provides, as herein illustrated, an improved shoe press having, in combination, a shoe support, a pressure applying member, and means for effecting relative movement between the support and the pressure applying member to apply initial pressure to a shoe in the press. After initial pressure has been applied, the press is provided with further means for applying additional pressure to the shoe and for holding or maintaining this pressure as long as may be desired. Moreover, in accordance with a feature of the invention, the additional pressure may be increased as much as may be desired or as may be required for the particular type of shoe being operated upon, thereby insuring a satisfactory attachment of the sole to the shoe bottom.

As herein illustrated, the shoe support preferably comprises a yieldable pad mounted in a pad box of usual construction supported on a stationary base portion of the press. The pressure applying member comprises an abutment provided with work engaging portions adapted to engage the forepart of the shoe and top of the heel portion of the last in the shoe, this abutment being adjustably mounted on a heightwise movable member whereby the abutment may be moved into and out of engagement with the shoe, the heightwise movable member being normally urged into its initial or inoperative position by resilient means. Means is provided for moving the pressure applying member or abutment against the shoe on the support to apply initial pressure to the shoe, this means preferably being treadle operated.

For applying additional pressure to the shoe, the press is provided with an operator controlled intermittent grip device which, as herein illustrated, is adapted to act upon the heightwise movable member and through it to cause the pressure applying member to apply additional pressure to the shoe. As illustrated herein, the

2

intermittent grip device includes an oscillatable actuating member and connections between said member and the heightwise movable member constructed and arranged to grip said movable member when the actuating member is oscillated in a pressure applying direction to move the pressure applying member toward the support to apply additional pressure to the shoe, said connections being also arranged, when the actuating member is moved in the opposite direction to its pressure applying movement, to grip the movable member and lock it against reverse movement away from the support, thereby holding the pressure on the shoe. In order to release the connections which lock the heightwise movable member against reverse movement and thereby relieve the pressure on the shoe, the actuating member is arranged to be moved a distance greater than its pressure applying movement in the opposite direction to said pressure applying movement.

As illustrated herein, the connections between the actuating member and movable member preferably include a plurality of superimposed pinch plates for gripping the heightwise movable member and moving it toward the support to cause the pressure applying member to apply additional pressure to the shoe, and a plurality of superimposed pinch plates for gripping the movable member and locking it against movement away from the support after the pressure has been applied, the two sets of plates operating alternatively under the action of the oscillatable actuating member.

With the above and other objects and features in view, the invention will now be described in detail in connection with the accompanying drawings and will thereafter be pointed out in the claims.

40 In the drawings:

Fig. 1 is a front elevational view of a machine embodying the present invention with parts broken away or shown in section;

Fig. 2 is an enlarged side elevation of the machine as viewed from the left in Fig. 1;

Fig. 3 is a further enlarged detail view of the pressure applying mechanism of the machine with portions broken away or shown in section;

Fig. 4 is a sectional view on a reduced scale taken on the line IV—IV of Fig. 3; and

Fig. 5 is a fragmentary view partly in section of a portion of the mechanism shown in Fig. 3 located in an operated position.

The illustrated shoe press comprises a stationary base or table 10 upon which is mounted a

frame 12 provided with a plurality of upstanding posts 14 having secured to their upper ends a supporting plate or casting 16. Mounted in the lower portion of the frame 12 are stationary shoe supports 18 in the form of pad boxes in which are mounted yielding pads 20 which, as illustrated in Figs. 1 and 2, preferably comprise hollow bags or bladders filled with fluid such as water, and having upper surfaces arranged to support a sole A and a shoe B, the sole being illustrated herein as a half sole adapted to be attached by cement to the forepart of the shoe. The machine is illustrated as a duplex or two-station machine capable of handling right and left shoes but since the operating instrumentalities of both stations are substantially the same in construction and operation, only the station which operates on the left shoe, illustrated at the left in Fig. 1, will be described in detail herein.

Secured by screws to the upper side of the plate 16 is a hollow casing 22. Extending through this casing is a heightwise movable shaft 24, the lower end of which is provided with a shoulder 23 (Fig. 3) and a narrow ear 25, the latter carrying a transverse pin 26 upon which is pivoted a coupling 28 provided with a T-shaped guideway 30. Adjustably mounted in the guideway 30 is a pressure applying member 32 which, as illustrated in Fig. 2, is provided at its forward or right-hand end with an abutment 34 arranged to engage the forepart of the shoe B, the member 32 having an offset inner portion 36 provided with a horizontal lower surface 38 adapted to engage the top of the heel portion of a last L in the shoe.

The shaft 24 is normally urged upwardly into an inoperative position by a spring 40 which surrounds a reduced upper portion 42 of the shaft and is confined thereon by a washer 44 and nut 46, the lower end of the spring engaging the upper end of the casing 22. The upper portion of the shaft 24 and the spring 40 are enclosed by a cylindrical housing 48 secured by screws to the casing 22. The upper or inoperative position of the shaft 24 is determined by the engagement of a collar 50 secured to its lower end with the lower surface of the casing 22, as shown in Fig. 3. The collar 50 is provided with a laterally extending arm 52 (Figs. 1 and 2) to which is secured a treadle rod 54 which extends downwardly to a treadle 55 whereby the shaft 24 may be moved downwardly to bring the pressure applying member 32 into engagement with the shoe B and last L, release of the treadle permitting the spring 40 to return the shaft and member 32 into their elevated positions with the collar 50 engaging the casing 22. Depression of the treadle 55, therefore, moves the pressure applying member 32 into engagement with the last and shoe and forces the shoe and sole against the shoe support 20 to apply initial pressure to the shoe.

The shaft 24 is maintained in its lowered position to hold the pressure by mechanism illustrated in Figs. 3 to 5, inclusive. This mechanism comprises an intermittent grip device which not only holds the initial pressure applied by depression of the treadle 55, but operates through the movable shaft 24 to cause additional pressure to be applied to the shoe and also to hold this additional pressure until the grip device is actuated to release the pressure applying mechanism and relieve the pressure on the shoe.

The casing 22 has an inwardly projecting horizontal portion 56 provided with a U-shaped opening which straddles the shaft 24. Mounted above the portion 56 are a plurality of superimposed

gripping members or pinch plates 58 provided with holes slightly larger in diameter than the shaft 24 and through which the shaft passes, the left-hand ends of the pinch plates, as viewed in Fig. 3, extending into an opening 60 in the casing which confines these ends against heightwise movement but permits limited pivotal or swinging movement of the plates about centers located at or adjacent to the opening. A spring 62, surrounding the shaft 24 and seated in a recess in the portion 56 of the casing, normally urges the pinch plates upwardly and thus tilts them at an angle, as shown in Fig. 3, sufficiently to cause the plates to grip the shaft 24 and thereby prevent any movement of the shaft in an upward direction away from the support or pad 20 while the plates are tilted, the tilted plates, however, permitting movement of the shaft in a downward or pressure applying direction under force sufficient to overcome the spring 40. The pinch plates 58, therefore, constitute in effect detents for gripping the shaft 24 and locking it against upward movement until the plates are released from the shaft, thereby holding the initial pressure applied to the shoe by depression of the treadle 55.

Located below the horizontal portion 56 of the casing is a plurality of superimposed pinch plates 64 provided with aligned holes slightly larger than the diameter of the shaft 24 and through which the shaft passes, these plates being normally urged upwardly into a horizontal position against the portion 56 by a spring 66 surrounding the shaft and extending between the plates and the bottom of the casing, the shaft passing freely through the holes in the plates when the latter are located in a horizontal position, as shown in Fig. 3. When the pinch plates 64 are tilted into an angular position, however, they will grip the shaft 24 similarly to the upper plates 58 and will force the shaft to move bodily with the plates as long as the latter remain in a tilted position.

The plates 64 are tilted to grip the shaft 24 and move it downwardly to cause the pressure applying member 32 to apply further pressure to the shoe on the support 20, that is, pressure in addition to the initial pressure applied by depression of the treadle 55. The casing 22 is provided with a horizontal guideway 68 (Figs. 1 and 2) in which is mounted a bracket 70 having a boss 72 thereon provided with a horizontal bore 73 (Fig. 4) in which is rotatably mounted by means of needle bearings 74 a short horizontal shaft 76. The shaft 76 has a rectangular outer portion 78 upon which is mounted a long oscillatable actuating member or handle 80 which is maintained on the rectangular portion by a nut 82 threaded on a reduced end 84 of the shaft.

An inner portion 86 of the shaft 76 is enlarged in diameter, as illustrated in Fig. 4, and is provided at one side with a wide vertical slot 88 and at an opposite side with a second vertical slot 90 somewhat narrower than the slot 88. The slot 90 breaks into the wider slot 88 below the axis of the shaft, as viewed in Fig. 3, to leave a substantially rectangular intermediate or bridge portion 92 extending between the portions of the shaft at opposite sides of the two slots. Mounted between the opposite sides or ears of the portion 88 formed by the slot 88 is a horizontal pin 94 which, as shown in Figs. 3 to 5, inclusive, overlies and engages laterally projecting arms 96 formed on the right-hand sides of the lower pinch plates 64. Accordingly, when the actuating member or handle 80 is oscillated in a counter-clockwise direction, as viewed in Fig. 3, the pin 94 will tilt the

pinch plates 64 out of their horizontal position against the action of the spring 66, thereby causing the plates to grip the shaft 24. Continued movement of the handle 80 in that direction will move the plates and shaft 24 downwardly to force the pressure applying member 32 more firmly against the shoe and thereby apply additional pressure to the shoe and sole on the support. The position of the parts when additional pressure is being applied is illustrated in Fig. 5.

Oscillation of the handle 80 in the opposite direction to its pressure applying movement, that is, in a clockwise direction as viewed in Fig. 3, moves the pin 98 upwardly away from the pinch plates and permits the plates to assume a horizontal position under the action of the spring 66, thereby releasing the grip of the plates on the shaft 24. The spring 66 forces the plates upwardly along the shaft until they engage the horizontal lower surface of the projection 56 of the casing, thereby maintaining the plates in a horizontal position. During movement of the plates 64 upwardly along the shaft 24, the shaft remains locked in its lower position by reason of the upper pinch plates 58, thereby holding the increased pressure on the shoe, the upper plates 58, as indicated above, being tilted at an angle at this time to cause them to grip the shaft and lock it against reverse or upward movement away from the support 28 although permitting downward movement of the shaft. Consequently, in the operation of the machine the operator, after depressing the treadle 55 and removing his foot therefrom, oscillates the handle 80 alternately downwardly in a counter-clockwise direction and then upwardly and he repeats this operation as many times as may be necessary to apply the desired pressure to the shoe, the shaft 24 being forced downwardly with each counter-clockwise movement of the handle by the lower pinch plates 64 and being retained against reverse or upward movement, when the lower plates are released, by the upper pinch plates 58 which lock the shaft in its lowered position at the end of each downward stroke of the handle and thereby hold the increased pressure applied to the shoe. The two sets of pinch plates, therefore, constitute alternately operating means for applying additional pressure to the shoe and for holding the additional pressure until it is released.

After sufficient pressure has been applied to the shoe for a period of time long enough to insure the permanent attachment of the sole A to the forepart of the shoe B, the pressure on the shoe is relieved and the pressure applying member 32 is returned to its upper or inoperative position with the collar 50 bearing against the lower end of the casing 22, as shown in Fig. 3. In order to release or unlock the shaft 24 and permit the spring 40 to elevate it to its initial position, the inner portion 98 of the horizontal shaft 16 is provided with a pin 98 which extends between the opposite side walls of the slot 96 and rides in an elongated slot 100 formed in the lower portion of a rod or link 102 the upper end of which extends loosely through a bell-shaped hole formed in a horizontal arm 104 overlying and engaging the free ends of the plates 58 and pivoted in a slot in the casing on a pin 106, the rod 102 being connected to the arm 104 by lock nuts 108 threaded on the rod.

During the normal operation of the mechanism in applying additional pressure to the shoe, the pin 98 merely rides up and down in the slot 100 in the rod 102, as illustrated in Figs. 3 and 5.

When it is desired, however, to relieve the pressure on the shoe, the oscillatable handle 80 is moved in a clockwise direction, as viewed in Fig. 3, a greater distance than is necessary for applying increased pressure to the shoe. In other words, the handle 80 may be swung in a clockwise direction into a nearly vertical position whereby the pin 98, which is then located at the lower end of the slot 100, will be moved further downwardly to lower the rod 102 and swing the arm 104 downwardly about its pivot 106, thereby moving the right-hand ends of the pinch plates 58 downwardly to locate the plates in a substantially horizontal position which will release the grip or bite of the plates on the shaft 24 and unlock the shaft to permit the spring 40 to elevate it to its initial or inoperative position, the treadle 55 also being returned to its elevated position by the spring. In this way after the desired pressure has been applied to the shoe for a sufficient period of time to insure a permanent attachment of the sole to the shoe bottom, the pinch plates 58 are released to unlock the shaft 24 and thereby relieve the pressure on the shoe.

In order that the actuating handle 80 may be normally located in a position in which the mechanism is ready to operate, that is, with the pin 98 engaging the lower plates 64, the handle is provided with a boss 110 (Figs. 3 and 4) opposite an upper portion of the casing 22 in which is mounted a spring-pressed plunger 112 having a rounded end. The plunger 112 is arranged to snap into a cone-shaped recess 114 formed in the adjacent portion of the casing and thus hold the handle 80 normally in the position referred to, the construction being such that the rounded end of the plunger will slip readily by the recess 114 when the handle is oscillated further in a clockwise direction to release the pressure on the shoe. When the handle 80 is located in its inoperative position with the plunger 112 engaging the recess 114, the pin 98 will be located approximately at the lower end of the elongated slot 100 in the link 102 and the horizontal arm 104 will be resting by gravity on the upper pinch plates 58 so that these plates, as illustrated in Fig. 3, will be normally tilted out of the horizontal relatively to the shaft 24 by the spring 62 and will thus be in a position which will permit the shaft to be moved downwardly toward the shoe support or pad 28 but will not allow the shaft to be moved upwardly in a reverse direction away from the support.

Having thus described my invention, what I claim as new and desire to secure by Letters Patent of the United States is:

1. A shoe press having, in combination, a shoe support, a pressure applying member, means for effecting relative movement between said member and said support to apply initial pressure to a shoe in the press, operator controlled intermittent grip means for applying further pressure to the shoe, and means separate from said intermittent grip means for maintaining said further pressure.

2. A shoe press having, in combination, a shoe support, a pressure applying member, operator controlled means for effecting relative movement between said member and said support to apply initial pressure to a shoe in the press, a manually operated intermittent grip device for causing said pressure applying member to apply additional pressure to the shoe, and single means for automatically holding said initial and said additional pressures.

3. A shoe press having, in combination, a shoe support, a pressure applying member, treadle operated means for causing relative movement between said member and said support to apply initial pressure to a shoe on the support, a manually controlled intermittent grip device connected to said pressure applying member for applying additional pressure to the shoe, and grip means separate from said device for automatically maintaining said pressure.

4. A shoe press having, in combination, a shoe support, a pressure applying member, operator controlled means for effecting relative movement between said member and said support to apply initial pressure to a shoe in the press, manually operated intermittent grip means for causing said member to apply increased pressure to the shoe after the initial pressure has been applied, said grip means operating alternatively to grip and release said pressure applying member, and means for automatically maintaining said pressure when the grip means releases said member.

5. A shoe press having, in combination, a shoe support, a pressure applying member opposite said support, treadle operated means for moving said member relatively to the support to apply pressure to a shoe thereon, a heightwise movable member connected to said pressure applying member, manually controlled intermittent grip means arranged to transmit force through said movable member to the pressure applying member thereby to increase the pressure applied to the shoe by said treadle operating means, and means independent of said grip means for automatically maintaining said pressure.

6. A shoe press having, in combination, a shoe support, a pressure applying member, means for effecting relative movement between said member and said support to apply initial pressure to a shoe on the support, a plurality of pinch plates operable to effect further relative movement between said pressure applying member and said support to apply additional pressure to the shoe, and means for operating said pinch plates.

7. A shoe press having, in combination, a shoe support, a pressure applying member, treadle operated means for moving said member toward said support to apply initial pressure to a shoe thereon, intermittently operating grip means for moving the pressure applying member further toward the support to apply additional pressure to the shoe, and separate means for automatically locking said member against movement away from the support to hold said additional pressure after each intermittent operation of said grip means.

8. A shoe press having, in combination, a support, a pressure applying member, a plurality of alternately operating pinch plates, one for effecting relative movement between said member and said support to apply pressure to a shoe thereon and the other for preventing relative movement between said member and said support to hold said pressure, and manually controlled means for operating said pinch plates.

9. A shoe press having, in combination, a shoe support, a pressure applying member opposite said support, a plurality of pinch plates arranged respectively to move said member toward the support to apply pressure to a shoe thereon and to lock said member against movement away from the support to hold said pressure, and oscillatable means for operating said pinch plates alternatively, said means being also arranged to release

the locking plates to relieve the pressure on the shoe.

10. A shoe press having, in combination, a shoe support, a pressure applying member, means for moving said member toward the support to apply initial pressure to a shoe thereon, a plurality of alternately operating pinch plates, one for moving the pressure applying member further toward the support to apply additional pressure to the shoe and the other for locking said member against movement away from the support to hold said additional pressure, means for operating said pinch plates alternatively, and means for returning said pressure applying member to inoperative position.

11. A shoe press having, in combination, a shoe support, a pressure applying member opposite said support, means for moving said member toward the support to apply initial pressure to a shoe thereon, a manually controlled intermittent grip device for causing said member to apply additional pressure to the shoe, said device including a plurality of pinch plates for moving said member further toward the support to apply said additional pressure, and a plurality of pinch plates operating alternatively with said first-named plates for locking said member against movement away from the support to hold said additional pressure.

12. A shoe press having, in combination, a shoe support, a heightwise movable member opposite said support, a pressure applying member carried by the movable member, treadle operated means for moving said movable member toward the support to cause the pressure applying member to apply initial pressure to a shoe thereon, a plurality of superimposed pinch plates for gripping said movable member and moving it further toward the support to apply additional pressure to the shoe, a plurality of superimposed pinch plates for gripping said movable member and preventing movement thereof away from the support thereby holding said additional pressure, and means for actuating the two sets of pinch plates alternatively.

13. A shoe press having, in combination, a shoe support, a pressure applying member opposite said support, a heightwise movable shaft connected to said member, treadle operated means for moving said shaft toward the support to cause the pressure applying member to apply initial pressure to a shoe thereon, a plurality of superimposed pinch plates for gripping said shaft and moving it further toward the support to apply additional pressure to the shoe, a plurality of superimposed pinch plates for gripping said shaft and locking it against movement away from the support to hold said additional pressure, and oscillatable means for operating the two sets of pinch plates alternatively, said oscillatable means being also arranged to release the locking plates and thereby relieve the pressure on the shoe.

14. A shoe press having, in combination, a shoe support, a pressure applying member, operator controlled means for effecting relative movement between said support and said pressure applying member to apply initial pressure to a shoe in the press, and an operator controlled intermittent grip device for causing said member to apply additional pressure to the shoe, said device including an oscillatable actuating member, a detent for holding the pressure applied to the shoe, and connections between said oscillatable member and the detent constructed and arranged

to release said detent when the oscillatable member is moved in a direction opposite to its pressure applying movement.

15. A shoe press having, in combination, a shoe support, a pressure applying member, a heightwise movable shaft connected to said member, treadle controlled means for moving said shaft to cause said member to apply initial pressure to a shoe in the press, manually controlled intermittent grip means for causing said member to apply additional pressure to the shoe, said means including an oscillatable actuating member, and connections between said actuating member and said shaft constructed and arranged to grip the shaft upon movement of the actuating member in a direction to apply said additional pressure, said connections being also arranged upon movement of the actuating member in an opposite direction to lock the shaft against movement in an opposite direction to its pressure applying movement, thereby holding said additional pressure.

16. A shoe press having, in combination, a shoe support, a pressure applying member, treadle operated means for moving said member toward the support to apply initial pressure to a shoe thereon, a heightwise movable shaft connected to said pressure applying member, a manually controlled intermittent grip device arranged to act upon said shaft to apply additional pressure to the shoe through said pressure applying member, said intermittent grip device including an oscillatable actuating member, a detent associated with said shaft for holding the additional pressure applied to the shoe, and connections between said oscillatable member and the detent constructed and arranged to release said detent when the oscillatable member is moved a distance

greater than its pressure applying movement in the opposite direction to said pressure applying movement.

17. A shoe press having, in combination, a shoe support, a pressure applying member, treadle operated means for moving the pressure applying member toward the support to apply initial pressure to a shoe thereon, and operator controlled intermittent grip means for causing said member to apply additional pressure to the shoe, said means including a heightwise movable shaft, means normally urging said shaft away from the shoe, an oscillatable actuating member, a plurality of pinch plates between said actuating member and said shaft arranged to grip the shaft and move it further toward the support to apply additional pressure to the shoe upon movement of the actuating member in a pressure applying direction, a plurality of pinch plates arranged to grip said shaft and lock it against reverse movement to hold said additional pressure, and connections between said last-named pinch plates and said actuating member constructed and arranged to release said plates upon movement of the actuating member a distance greater than its pressure applying movement in the opposite direction to said pressure applying movement, thereby relieving pressure on the shoe.
